UNITED STATES PATENT OFFICE.

JACOB J. KAHN, OF MONTREAL, QUEBEC, CANADA, ASSIGNOR OF ONE-HALF TO SAMUEL HART & COMPANY, OF MONTREAL, CANADA.

GARMENT.

1,223,394.

Specification of Letters Patent. Patented Apr. 24, 1917.

Application filed September 4, 1915. Serial No. 49,008.

To all whom it may concern:

Be it known that I, JACOB J. KAHN, a citizen of the Dominion of Canada, and resident of the city of Montreal, in the Province of Quebec and Dominion of Canada, have invented certain new and useful Improvements in Garments, of which the following is a full, clear, and exact description.

10 This invention relates to improvements in garments, and particularly to the type known as convertible garments.

15 The object of the invention is to provide a garment particularly adapted for men's wear, which may be worn either as a coat alone or as a coat and vest.

20 The usefulness of such an article of clothing will be readily appreciated by anyone who has occasion to be much in the open air, and therefore subject to sudden changes of temperature. The garment will also be appreciated by those who unexpectedly find themselves under circumstances where the wearing of a vest or the lack of 25 a vest would be inappropriate.

25 The arrangement and operation of the invention is the attaching of a pair of flaps to a coat provided with interior pockets into which the flaps may be folded when 30 they are not being used as a vest. Such an arrangement, while apparently very easy of execution, presents a number of difficult features from the tailoring point of view, and which if not properly solved render the resulting garment both uncomfortable and ludicrous. This invention is therefore more particularly directed to these 35 details of construction which are essential to the production of a comfortable and 40 slightly garment, one of which is the fitting of the vest flaps around the collar and another the connection between the vest flap and coat, which avoids dragging the coat and which permits the wearer to easily 45 draw back the coat when putting his hands in his trouser pockets.

In the drawings which illustrate the invention:

50 Figure 1 is a perspective view of the garment worn as a coat and vest.

Fig. 2 is a perspective view of the garment worn as a coat only.

55 Fig. 3 is a partial interior view of the garment showing the arrangement thereof.

Referring more particularly to the draw-

ings, 11 designates the shell of a coat which is of any usual form, and 12 the lining thereof. A pocket 13 is formed between the shell and lining opening at the junction of the facing 14 and lining and extending 60 from the top of the shoulder to approximately the waist line, and as far toward the back of the coat as desired, within the limits set by the arm hole 15. A flap 16 representing one half of a vest is secured 65 to each side of the coat at the inner edge of the facing in such a manner that it may be folded within the pocket 13, or withdrawn and extended across the wearer's body to form part of a vest front. The 70 upper end of each flap 16 tapers until approximately only an inch wide at about the point where the shoulder and collar seams of the coat join, and is then cut off square and provided at the outer corner with a 75 suitable fastener 17 engageable with its component part 17^a on the coat collar, so as to hold the vest close to the coat collar when in extended position. The purpose 80 and use of this feature is to hold the edge of the vest well up and prevent it catching under the wearer's shirt collar.

At the lower end, each flap 16 is provided with a rearwardly projecting arm or extension 18, which terminates in an elastic portion 19 located between the shell and lining of the coat. These elastic portions 19 may be secured so that the two halves of the vest are connected across the back and the vest thus held snugly to the body. The 90 lower portion of the flap 16 carrying the projecting arm 18 is not secured to the coat of itself, but is entirely separate, as clearly shown in Fig. 3. It will thus be seen that the line of connection 20 between the coat 95 and vest flap extends from the upper end of the vest flap a suitable distance toward the bottom, and terminates at least the depth of the arm 18 from the lower end of the flap. These extensions 18 and the elastic portion 19 hold the flaps, when worn as a vest, yieldably to the body, while the separation of the vest flaps and coat in the lower portion permits the coat to be easily drawn back, as in placing the hands in the trouser pockets, without dragging on the vest flaps or wrinkling the coat in such a manner as to make it perfectly obvious that the garment is a combination one. The rear edge of the coat facing and the forward 110

edge of the lining are provided with co-operating fasteners 21 which serve to releasably secure the lining to the facing when the vest flaps are folded within the 5 pockets 13. These fasteners are concealed by the lining during folded position of the vest flaps, and are placed so close to the attachment of the coat and vest flaps that when the flaps are extended and in use, the 10 fasteners are invisible, unless the coat is deliberately held open in such a way as to exhibit same.

The operation of the garment is extremely simple, and will be readily understood. 15 When it is desired to wear the same as a coat only, the flaps 16 are folded into the pockets 13 and the lining secured to the facing by means of the fasteners 21 to close the pockets, rendering the same invisible 20 and confining the vest flaps therein. When it is desired to wear the garment as a coat and vest, the lining and facing are separated and the flaps withdrawn and buttoned over the wearer's body in the ordinary manner. 25 Before securing the flaps one to the other, the upper corners of the same are secured to the coat collar by means of the

fasteners 17, 17^a, so that the upper edges of the vest flaps are held well up and slightly away from the wearer's body, so 30 that they will not catch under the wearer's shirt collar, thus producing a discomfort and unsightly appearance. The operation of the garment may easily be effected while the same is being worn, and in an extremely 35 short space of time.

Having thus described my invention, what I claim is:—

In a garment, a coat provided with facing and lining and having inside pockets 40 opened from the front at the junction of the facing and lining, a flap permanently secured to each side of the coat immediately within the pocket opening and releasably 45 securable at its upper end to the coat when withdrawn from the pocket, said flaps being unconnected with the coat in their lower portions, rearward extensions of the flaps in the portions thereof unattached to 50 the coat, and elastic connections between said rearward extensions and the coat.

In witness whereof, I have hereunto set my hand.

JACOB J. KAHN.
